UNITED STATES PATENT OFFICE

WILLIAM H. GROVER AND WILLIAM S. POOLEY, OF TOLEDO, OHIO, AND CLARENCE E. MERRITT, OF ADRIAN, MICHIGAN

CIRCUIT CLOSER

Original application filed April 1, 1926, Serial No. 99,047. Divided and this application filed March 16, 1928. Serial No. 262,180.

This invention relates to a circuit closer which is adapted to control the successive closing and opening of a plurality of electric circuits at predetermined time intervals. The 5 invention, in its present embodiment, is intended primarily for use in an elevator signal system, such as is disclosed in our U. S. Patent No. 1,731,975 issued Oct. 15, 1929, of which the present application is a division. 10 It will be readily seen, however, that a circuit closer of substantially the same construction may be used in connection with a great variety of electrically operated devices which it is desirable to control in a similar manner. 15 One of the objects of the present invention is to provide a circuit closer which is capable of controlling any number of circuits and which is provided with improved adjusting means for varying the time of opening and 20 closing the various circuits.

A further object of the invention is to provide a convenient arrangement containing a plurality of sets of contacts and selective means whereby any of said sets of contacts 25 may be rendered operable.

The specific construction of the invention as at present constructed, and its mode of operation, will be described in detail in connection with the accompanying drawings, 30 in which:—

Figure 1 is a plan view of the invention.

Fig. 2 is a central sectional view through one unit of the invention, showing the same on an enlarged scale.

Fig. 3 is a longitudinal sectional view of one pair of brushes used in connection with the invention.

Fig. 4 is a wiring diagram of an electrical system which may be controlled by the circuit closer.

As illustrated in Figs. 1 and 2, the several parts of the circuit closer are arranged about a shaft 7, which is rotatably supported and 45 driven by any suitable means, as for example through the medium of a gear 8 secured to the shaft. The circuit closer may have any number of like units, each comprising one or more switch arms 48, 49, rotatable with the 50 shaft, and a fixed commutator 11, having for

each switch arm a set of segments 57, 58 arranged concentric with the shaft.

Each of the switch arms 48 and 49 carries a pair of brushes, as indicated at 50 and 51, respectively. These brushes are set tangentially, as shown in Fig. 4, and may be adjusted in the direction of their length, to vary the times at which they make or break contact with the segments 57 and 58, respectively. To provide for this adjustment, each brush is slotted, as shown at 28 in Fig. 3, and is secured to the arm 48 or 49 as the case may be, by a bolt 29 which passes through the slot and is secured by a nut 30.

For mounting each set of switch arms 48 and 49, a pair of insulated bushings 31 and 32, coupled to each other by one or more bolts 42, are secured to the shaft 7 by a suitable key 43, which may be inserted through a hub formed on one of the bushings, as shown in Fig. 2. These bushings are provided with circumferential channels in which contact rings 33 and 34 are housed. The arms 48 and 49 are secured to rings 44 and 45 respectively, which are individually adjustable circumferentially of the respective rings 33 and 34 and which may be secured in any position of adjustment by set screws 46 and 47. Concentrically arranged collector rings 35 and 36 are fixed on the outer face of one of the bushings, as 31, and are adapted to make contact with the brushes 37 and 38, which are supported by a suitable bracket 39. The collector rings 35 and 36 are electrically connected with the contact rings 33 and 34, respectively, through the bolts 40 and 41.

The brushes 50 and 51 cooperate with the series of segments 57 and 58, respectively, which are carried by the commutator 11 and which are insulated from each other.

The brush 38 contacting with the collector ring 36 is connected through the wire 52 to a source of electric energy 53 and through the wire 54 and switch 55 to electric signals or other devices 56, which are in common circuit. The other sides of electrical devices 56 are connected to respective sets of segments 57 and 58 of the commutator 11. The other circuit is connected from brush 37 through a wire 59 to a source of electrical energy 60 109

and thence by a wire 61 and the switch 55 to the common side of the electrical devices 56. The switch 55 is common to both circuits and when moved to close one circuit, opens the other.

5 From the foregoing description, it will be understood that each of the rings 44 and 45 of each unit may be individually adjusted circumferentially about the contact ring with 10 which it is associated; each brush of each pair 50 and 51 may be individually adjusted longitudinally of the arm by which it is carried; and a switch 55 may be actuated to render operable either the inner series of segments 15 58 through the brushes 51 or the outer series of segments 57 through the brushes 50. It is also obvious that by this adjustment of the rings 44 and 45 of different units, the contacts of one unit may be set behind or 20 ahead of the contacts of any other unit. In the operation of a number of units, this greatly reduces the maximum load and consequently lowers the cost of the current consumed.

25 It will be apparent to those skilled in the art that the present invention may be used in connection with many different kinds of signal systems and other electrical installations and that many modifications may be 30 made in its specific construction without any material departure from the spirit and scope of the invention. It is our intention, therefore, to include all such modifications within the scope of the appended claims.

35 What we claim is:

1. In a circuit closer, a commutator having concentric rows of segments and a rotatable member cooperating therewith including interconnected bushings, contact rings 40 positioned on said bushings, brush arm carrying rings adjustable circumferentially of said contact rings, brush arms carried by the respective adjustable rings, and means for locking said adjustable rings in the desired setting.

2. In a circuit closer, a commutator having concentric rows of segments and a rotatable member cooperating therewith, said rotatable member including interconnected bushings, contact rings positioned upon said bushings, rings adjustable circumferentially of said contact rings, means for locking said adjustable rings in the desired setting, brush 50 arms carried by the respective adjustable rings, and a switch arm operable to establish a circuit through one of said arms to the exclusion of any other of said arms.

3. In a circuit closer, a commutator having concentric rows of segments, spaced brush arms for the respective rows, means for rotating said brush arms, and a pair of brushes carried by each arm in cooperative relation to the respective row of segments, 65 each brush of each pair being individually

adjustable in a direction substantially tangential to its path of movement.

4. In a circuit closer, a commutator having concentric rows of segments and a rotatable member including interconnected bushings, contact rings positioned on said bushings, brush arm carrying rings adjustable circumferentially of said contact rings, brush arms carried by the respective adjustable rings, a pair of brushes carried by each arm 70 in cooperative relation to the respective row of segments, each brush of each pair being individually adjustable in a direction substantially tangential to its path of movement, and means for locking said adjustable rings in the desired setting.

5. A circuit closer comprising a plurality of units, each unit including a commutator with a series of segments insulated from each other, a shaft common to all units, means for 85 rotating said shaft, brush carrying arms supported by the shaft for cooperation with the respective series of segments, and means for selectively adjusting the brush carrying arm of each unit about the shaft, independently of the other units.

6. A circuit closer comprising a plurality of units, each unit including a commutator with a series of segments insulated from each other, a shaft common to all units, means for 95 rotating said shaft, brush carrying arms supported by the shaft for cooperation with the respective series of segments, a pair of brushes carried by each arm for engaging the segments, each brush of each pair being individually adjustable in a direction substantially tangential to its path of movement, and means for selectively adjusting the brush carrying arm of each unit about the shaft, independently of the other units.

7. A circuit closer comprising a plurality of units, each unit comprising a series of contacts and a brush engageable successively with said contacts, means for moving all of the brushes simultaneously over the respective series of contacts, and means for individually and selectively setting each brush forwardly or backwardly with respect to the other brushes.

In testimony whereof, we have hereunto signed our names to this specification.

WILLIAM H. GROVER.

WILLIAM S. POOLEY.
